HERMETICALLY-SEALED THERMOSTAT

Bernard F. Parr, Mansfield, Ohio, assignor to
Westinghouse Electric Corporation, East Pitts-
burgh, Pa., a corporation of Pennsylvania

Application January 18, 1947, Serial No. 722,851

2 Claims. (Cl. 200—138)

1

My invention relates to thermostats, more particularly to thermostats which are sealed within fluid-tight casings, and has for an object to provide an improved thermostat of this kind.

A further object of my invention is to provide an improved hermetically-sealed thermostat for use with electrically-heated bed coverings, pads, uniforms and the like for preventing overheating thereof.

These and other objects are effected by my invention as will be apparent from the following description and claims taken in connection with the accompanying drawing, forming a part of this application, in which:

Fig. 1 is a view, partially in section and partially in elevation, of a thermostat constructed in accordance with my invention; and

Figs. 2 and 3 are, respectively, plan and end views of the thermostat shown in Fig. 1.

Reference will now be had to the drawing wherein I have shown an embodiment of my invention which is particularly adaptable for attachment to electrically-heated bed coverings, pads or uniforms, and which functions to prevent the overheating thereof. As apparatus of this kind is washed or dry cleaned periodically, it is desirable that the safety thermostats controlling their heating elements be isolated from the cleaning or washing fluid in order to prevent damage to the thermostat or the accumulation of cleaning fluid around the thermostat. The thermostatically-operated switch structure is generally indicated at 10 and may include a frame 11 having a stationary contact 12 fixed thereto and a movable contact 13 carried by a resilient support 14 and cooperating with the stationary contact 12. The resilient support is insulated from the frame 11 in any well-understood manner and a bimetallic member 15 having its high expansive metal uppermost is also carried by the frame 10 and functions to disengage the contacts 12 and 13 in response to a predetermined high temperature. Terminals 16 and 17 are electrically connected, respectively, to the frame 10 and the spring support 14 and conductors 18 and 19 are soldered or otherwise secured to the respective terminals 16 and 17. The conductors 18 and 19 may be electrically connected to the heating element of the apparatus (not shown) being controlled, or these conductors may be extensions of the heating element.

In accordance with my invention, the thermostatically-operated switch 10 is arranged within a relatively rigid housing 21 which may, for example, be formed of fiber tubing. An elongated

2

tubular shell 22 surrounds the tubular housing 21 and is somewhat longer than the housing 21 so that its ends are spaced outwardly from the ends of the housing 21. The insulating covering of the conductors 18 and 19 and the shell 22 are formed from thermoplastic material such as, for example, plasticized polyvinyl chloride. As shown, the ends of the shell 22 are crimped flat to close the ends of the shell 22 and to engage the insulation of the conductors 18 and 19. The crimping or flattening of the ends of the shells 22 may be effected in any well-understood manner such as, for example, by a pair of dies (not shown) which are heated during the flattening process sufficiently to cause the thermoplastic material of the shell and the insulation of the conductors 18 and 19 to flow and form an autogenous connection which is fluid-tight. Accordingly, the shell 22 defines a hermetic casing in which the thermostat 10 is enclosed. Preferably, the thickness of the insulation of the conductors 18 and 19 is increased at the points where the shell is connected thereto, as shown at 20, in order to provide additional material for forming the autogenous connection and to insure that the conductors will not be damaged by the dies during the sealing step just described.

Preferably, before sealing the ends of the shell 22, the conductors 18 and 19 are bent slightly, as shown at 23 and 24, in order to relieve any strain on the terminals 16 and 17 during the sealing-in process. Furthermore, the bends in the conductor also prevent the straining of the conductor or the terminals 16 and 17 if the ends of the shell 22 are bent in service, it being understood that a thermoplastic material, such as polyvinyl chloride, is relatively pliable.

From the foregoing description, it will be apparent that I have provided an improved hermetically-sealed thermostat structure having a thermoplastic casing connected autogenously to the insulation of the conductors extending therefrom. While I have described polyvinyl chloride as the preferred material for the shell, it will be understood that other thermoplastics may be employed. Furthermore, the rigid housing which encloses the switch effectively protects the switch from extraneous forces to which the structure may be subjected. The provision of a bend or additional length in the conductors between the autogenous seal with the shell and the switch structure prevents straining of the conductors or the switch terminals to which they are connected in the event that the ends of the shell are bent or distorted in service.

While I have shown my invention in but one form, it will be obvious to those skilled in the art that it is not so limited, but is susceptible of various changes and modifications without departing from the spirit thereof.

What I claim is:

1. In a hermetically-sealed thermostat structure, the combination of a thermostatically-actuated switch mechanism having a pair of terminals, a pair of conductors secured respectively to the terminals and having an insulating pliable thermoplastic covering, a relatively stiff housing surrounding the thermostatically-actuated switch mechanism and an elongated tubular thermoplastic shell surrounding said housing and having its ends spaced outwardly from the ends of the housing, said conductors extending outwardly through the respective ends of the thermoplastic shell, said ends of the thermoplastic shell being crimped to engage the thermoplastic covering of the respective conductors and heat treated to close the ends of the thermoplastic shell and to seal the same to the coverings of the conductors, said conductors having respective bends formed therein

intermediate said terminals and the portions of the conductors which are sealed to said shell.

2. The combination as claimed in claim 1 wherein said shell and covering for the conductors are formed of plasticized polyvinyl chloride.
